UNITED STATES PATENT OFFICE.

FRANK S. LIVINGSTON, OF LOS ANGELES, CALIFORNIA, ASSIGNOR TO SNOW MANUFACTURING COMPANY, OF LOS ANGELES, CALIFORNIA.

DOUBLE-LEVER GATE LOCK.

Application filed September 17, 1921. Serial No. 501,474.

To all whom it may concern:

Be it known that I, FRANK S. LIVINGSTON, a citizen of the United States, residing at Los Angeles, in the county of Los Angeles and State of California, have invented a new and useful Double-Lever Gate Lock, of which the following is a specification.

This invention relates to gate-valves and to devices for controlling the passage 10 through gate-valves.

One of the objects of this invention is to provide a simple gate-valve in which only the seat is to be machined, the base-plate or member having lugs to which channel-bars are secured to form the guide members for the cover-plate in relation to the seat 15 of the base-member.

Another object is to provide a locking lever pivotally supported on the cover-plate 20 of the valve in about its middle, having engaging ends of wedge-like shape to engage in the guiding channels of the base- or frame-member to press the cover-plate against the seat in the base-member.

Other objects will appear from the following description and appended claims as well as from the accompanying drawing, in which—

Fig. 1 is a front elevation of the complete 30 device.

Fig. 2 is a cross section through the frame or base-plate on line 2—2 of Fig. 1.

Fig. 3 is a cross section through the cover-plate on line 3—3 of Fig. 1.

Fig. 4 is a cross section through the operating mechanism on line 4—4 of Fig. 1, in slightly enlarged scale.

Fig. 5 is a front elevation of the operating lever in slightly modified form.

Fig. 6 is an end view of the engaging end of one of the levers.

Fig. 7 is an end elevation of a turning knuckle, to be used in combination with the operating lever illustrated in Fig. 8, instead 45 of the gear-knuckle illustrated in Figs. 1 and 4.

Fig. 8 is a front elevation of an operating lever in slightly modified form.

Fig. 9 is an end elevation of a turning knuckle in a still more slightly modified form.

The valve seat 10, surrounding the passage 11 of the valve, is provided on the base-plate 12. This base-plate is preferably 55 made of cast-iron or other similar suitable

material requiring little machine-work or practically no machine-work beyond the facing of the seat 10. Lugs 13 are provided on the base-plate 12 for securing the channel bars 14. The channel bars are preferably of standard rolled material to be cut of a length to reach from the surface to the point where the passage of a flow is to be controlled by a gate-valve of this type. In an irrigating system, such passage of water 60 is very often quite a distance below the surface. The base-plate is with this arrangement of a standard type and size. The channel bars are the guideways for the cover-plate, and any length of bars may 65 easily be secured to the base-plate to reach from the surface to any point below the surface for guiding the cover-plate in suitable relation to the passage and valve-seat in the base-plate, the bars being broken off 70 at 15, but it will easily be understood that the bars can be extended indefinitely higher.

The cover-plate 16 is provided with lugs 17 of a size to easily slide within the channels 14. At the points 18, the lugs are interrupted to allow the wedge-like engaging ends 19 of the operating lever 20 to reach into the channels for pressing the cover-plate 16 against the seat 10 of the base-plate, or eventually pressing the edges 80 of the cover-plate against the opposite shanks of the channels while the wedge-shaped engaging ends 19 of the lever engage with the other shanks, when the cover-plate is in a position above the valve-seat. 85 The end-elevation of the wedge-shaped engaging ends is illustrated in Fig. 6, the edge 21 being of a height to easily slip into the channel between the cover-plate and the opposite free shank of the channel, 90 while the edge 22 is of a height to tightly engage or lock the cover-plate with the operating lever at any point within the channels. The lugs 17 are of a height together with the seating face 23, see Fig. 3, to allow 95 the cover-plate to slip or pass over the seat 10 of the base-plate while the lugs slide within the channels, the cover-plate being only tightly seated by an engaging of the wedge-shaped ends 19 as described above. A boss 100 24 is provided in about the middle of the cover-plate to pivotally support the operating lever 20, the operating lever being arranged so as to press on the middle of the cover-plate when engaging with its engag- 110

ing ends 19 under the shanks of the channels 14, to assure an even engaging of the cover-plate on the whole seat of the base-plate, preferably but not necessarily, since 5 the wedge-shaped ends can also be arranged to wedge between the cover-plate and the shanks of the channels, as will easily be understood. Stop-lugs 25 are provided to limit the swinging movement of the operating lever 20.

In the illustrations in Figs. 1 and 4, the operating lever is shown as provided with teeth engaging with a geared knuckle 26 as indicated at 27. The geared knuckle 26 15 is mounted on the shaft or rod 28. The shaft 28 is turnably mounted in the lugs 29 and 30 on the cover-plate 16. To avoid boring and keying of the knuckle to the shaft, a square shaft is preferably used, the 20 knuckle being provided with a cored hole to fit on the square shaft. The turning movement being only very short, necessitating only a few teeth on the knuckle and on the operating lever, the knuckle can 25 easily be cored to provide a proper engagement between the knuckle and the operating lever. A bushing or sleeve 31, having a square hole or bore is provided on the square shaft 28 within the lug 29 to allow 30 a proper turning and fitting of the square shaft within the lug 29. The sleeve 31 is provided with a flange 32 seating and engaging on one side of the lug 29. A pin 35 33 being provided to secure the sleeve 31 to the shaft, at the same time preventing the sleeve from shifting endwise. A handle 34 is provided on the upper end of the shaft 28.

In Fig. 5, a slightly modified form of operating lever is illustrated, a plain bar-handle 35 projecting upwardly to control the engaging ends 19. This form can, of course, only be used where the gate-valve is not very far below the surface, so that 45 the handle 35 can freely swing from side to side. In cases where the gate-valve is disposed in stand-pipes of irrigating systems, this form can normally not be used, since the handle 35 is liable to strike against the walls of the standpipes without allowing the engaging ends 19 to fully lock or unlock, as will be easily understood.

The slightly modified forms illustrated in Figs. 7, 8 and 9 can easily be used in combination with the turning shaft 28, as described with reference to the illustrations in Figs. 1 and 4. The slightly different turning knuckles 36 and 37 can be substituted for the geared knuckle 26. The end 38 in Fig. 8 can be substituted for the geared end of the operating lever 20 as illustrated in Fig. 1 and 4. The pin-end 39 of the knuckle 36 in Fig. 7 can engage with the slot 40 of the end 38 of the operating lever 20 in Fig. 8. Instead of the slotted end 38,

a pin-like end similar to the pin-end 39 on the knuckle 36 can be provided on the lever 20 to engage with the fork-like end 41 of the knuckle 37 in Fig. 9. From the above, it will be understood, the operating mechanism can be modified without materially departing from the principal points of the invention. I do not limit myself to the specific details as illustrated in the drawing but only to the principle of the invention as described above with reference to the illustrations.

Having thus described my invention, I claim:

1. In a gate-valve, a base-plate having a passage therethrough with a surrounding valve seat, guiding channels on the base-plate having each one shank spaced from the face of the said valve seat, a cover-plate having an engaging face to co-act with the valve seat and having engaging edges projecting in the opposite direction from the cover-plate to coat with the spaced shanks of the guiding channels, and an operating lever on the cover-plate having wedge-shaped engaging ends to wedge between the cover-plate and the spaced shanks, the said engaging edges being broken away to allow free movements of said lever between said cover-plate and said spaced shanks and adapted to guide the cover-plate while the lever is in inoperative position.

2. In a gate valve, an operating lever having a pivot support, two engaging ends projecting in opposite directions from the pivot support having wedge-like terminations, and an actuating end projecting from the pivot support sidewise of the two engaging ends having means operative by a rotating member and adapted to swing in the same plane with the engaging ends around the pivot support.

3. In a gate-valve, a base-plate having a passage therethrough, a cover-plate for closing said passage, a locking member pivotally engaged with the said cover-plate and disposed to press the cover-plate against the base-plate and having a segmental gear-face projecting rearwardly, and a turning knuckle operatively engaged with the locking member.

4. In a gate-valve, a base-plate having a passage therethrough, a cover-plate, a locking member pivotally engaged with the cover-plate for a swinging movement transversely to the said passage and having wedge-like portions for pressing the cover-plate against the base-plate, and a turning knuckle with its axis disposed at practically right angles to the said passage and operatively engaged with the locking member for controlling the cover-plate in relation to the base-plate.

5. In a gate-valve, a base-plate having a passage therethrough, a cover-plate, a han-

idle-member turnably disposed on the cover-plate transversely to the passage, and a locking member pivotally engaged with the cover-plate for a swinging movement in a plane practically parallel to the axis of the turning handle having means to wedge between the cover-plate and certain portions of the base-plate and having other means for operatively engaging with the turnable handle-member.

6. In a gate-valve, an operating lever having a pivot support, two locking ends having wedge-like terminations, and an operating end in form of a segmental gear.

7. In a gate-valve, an operating lever having an operating portion in form of a segmental bevel gear facing practically in an axial direction in relation to the swinging movement of the lever.

8. In a gate-valve; a cover-plate; in combination with the guiding channels, a base

plate having a valve seat, and locking members disposed between the said cover-plate and certain portions of the said guiding channels; the cover plate having an engaging face to co-act with said valve-seat and having certain portions projecting in the opposite direction to slidably engage with the said guiding channels when the locking members are in inoperative position and disposed so that the said locking members can pass in between the said cover-plate and said guiding channels for locking the cover-plate.

In testimony that I claim the foregoing as my invention I have signed my name in the presence of two subscribing witnesses.

FRANK S. LIVINGSTON.
